UNITED STATES PATENT OFFICE.

HUBBARD F. HURD, OF TROY, NEW YORK, ASSIGNOR TO CLUETT, PEABODY & CO., INC.,
OF TROY, NEW YORK, A CORPORATION OF NEW YORK.

SOFT FOLD-COLLAR.

1,171,956.

Specification of Letters Patent. Patented Feb. 15, 1916.

Application filed March 29, 1915. Serial No. 17,634.

To all whom it may concern:

Be it known that I, HUBBARD F. HURD, a citizen of the United States, residing at Troy, county of Rensselaer, and State of New York, have invented certain new and useful Improvements in Soft Fold-Collars, of which the following is a specification.

The invention relates to such improvements and consists of the novel construction hereinafter described and subsequently claimed.

Reference may be had to the accompanying drawings, and the reference characters marked thereon, which form a part of this specification. Similar characters refer to similar parts in the several figures therein.

Figure 1 of the drawings is a front view in perspective of a soft fold-collar embodying my invention. Fig. 2 is a plan view of the broken-away ends of the collar showing the front side of the ends of the band, and the ends of the top opened out flat.

The invention relates to what are known in the trade as soft fold-collars, which have a folded-over top made of soft or unstarched fabric. In certain styles of such soft fold-collars the front ends of the folded-over top terminate in V-shaped points which extend a considerable distance below the bottom edge of the band, and in collars of this style it is found difficult to maintain in proper position in use these V-shaped points of the folded-over top.

The principal object of the present invention is to maintain in proper position, in the use of such a collar, the ends of the folded-over top where the same project below the band of the collar.

Referring to the drawings wherein the invention is shown in preferred form, 1 represents the band, and 2 the folded-over top, the latter, as well as the band if desired, being made of soft unstarched fabric.

The band has the usual short end, 3, and the usual interlocking long end, 4, adapted to be inserted between the band and folded-over top at the other end of the collar. The band is provided with the usual back button-hole, 5, and the usual front buttonholes, 6, in its ends, and may also be provided with a buttonhole, 7, in the long end, 4, adapted to engage a button, 8, fastened to the other end, 3, whereby the band can be attached to the neckband of a shirt, and the ends of

the band connected together in the usual manner.

In carrying out my invention I attach to the bottom edge of the long end, 4, of the band a pair of tabs, 9-9, which depend therefrom and are provided respectively with buttonholes, 10 and 11, and I attach to the inner side the respective ends of the folded-over top, 2, buttons, 12 and 13, adapted, when the front ends of the band are buttoned together by the usual front collar button inserted through the buttonholes, 6-6, to engage the respective buttonholes, 10 and 11, in the tabs, 9.

Such equivalent fastening devices as may be desired may be substituted for the buttons, 12 and 13, and the buttonholes, 10 and 11.

The buttons, 12 and 13, are preferably attached by blind-stitching or by stitching extending only through the inner plies of the folded-over top so that the fastening means is invisible on the front or exposed surface of the folded-over top.

In applying the collar it is buttoned upon the shirt-neckband in the usual manner, 80 with the scarf or necktie inserted between the band and folded-over top, after which the buttons, 12 and 13, are inserted in the respective buttonholes, 10 and 11.

The knot may be formed in the necktie 85 before or after the ends of the top are buttoned to the tabs, 9-9.

The tabs, 9-9, may be made separate from each other as shown in Fig. 1, or may be made integral with each other as shown 90 in Fig. 2.

What I claim as new and desire to secure by Letters Patent is—

1. A soft fold-collar having a band, a soft folded-over top with ends extending below the band and provided with fastening devices, and tabs attached to and depending below the band and provided with fastening devices adapted to engage the respective fastening devices on the ends of the 100 folded-over top.

2. A soft fold-collar having a band, a soft folded-over top with ends extending below the band, said band having a long end adapted to be inserted between the band and folded-over top at the other end of the collar, buttons attached to the inner side of the 105 respective ends of the folded-over top where

they extend below the band, and a pair of
buttonholed tabs attached to and depending
below the bottom edge of said long end of
the band and adapted to engage the respec-
5 tive buttons on the ends of the folded-over
top.

In testimony whereof, I have hereunto
set my hand this 23rd day of March, 1915.
HUBBARD F. HURD.
